UNITED STATES PATENT OFFICE.

GUSTAV ALBIN WALLIN, OF NEW YORK, N. Y., ASSIGNOR TO A. KIMBALL COMPANY, A CORPORATION OF NEW YORK.

PIN-TICKET.

No. 874,809.

Specification of Letters Patent.

Patented Dec. 24, 1907.

Application filed April 25, 1906. Serial No. 313,551.

To all whom it may concern:

Be it known that I, GUSTAV ALBIN WALLIN, subject of the King of Sweden, and resident of New York, county of New York, 5 State of New York, have invented certain new and useful Improvements in Pin-Tickets, of which the following is a specification.

I have devised a novel pin ticket having a pin permanently attached thereto and provided with means for easily attaching the ticket by means of the pin and effectively covering the pin point and preventing interference of the ticketed material with any other materials lying next to it or with which 15 the said material is liable to come in contact.

My invention is illustrated in the accompanying drawings, in which

Figures 1, 2 and 3 illustrate one form of pin ticket; Figs. 4 and 5 a modification; 20 Figs. 6, 7 and 8 another modification; Figs. 9 and 10 another modification; and Figs. 11 and 12 still another modification.

Referring to the first three figures of the drawing, 1 is a pin ticket and 2 a piece of 25 goods to which the said ticket is attached. The pin itself is shown at 3, the same being provided at 4 with a sharp end or point and at 5 with what may be called a head which is clenched into the material of the ticket. 30 The said ticket material may be cardboard, Manila paper, or other suitable paper or material capable of being easily marked. The ticket shown in Fig. 1 has an opening, 6, through which the pin point is thrust after 35 having passed twice through the goods.

The attachment of the pin ticket to the goods by means of a pin forming a permanent part of the ticket in the manner described is very simple and easy. The said 40 pin ticket 1 is also provided, as shown in Fig. 1, with a slot, 7, and a tongue, 8. After the pin ticket has been attached as described, the ticket is folded over along the line indicated at 9, Fig. 1, and the tongue 8 is thrust 45 from behind into the slot 7, whereby the pin point is fully covered and all danger of interference with adjacent goods is avoided.

Fig. 3 is a cross-sectional view through 50 the goods and the pin ticket illustrated in Figs. 1 and 2, and shows in dotted lines how the pin appears on being first thrust through the goods and in full lines how the pin lies after passing through the goods a second time and prior to the folding over of the 55 lower end of the ticket as described.

In Fig. 1, the part of the ticket above the folding line 9 is the pin-carrying portion, and the part below said line which is folded over directly upon the pin-carrying portion is termed the flap.

60

The arrangement in Figs. 4 and 5 differs from that already described mainly in the fact that the tongue 8 is formed on the shorter fold of the pin ticket 1 at one end of the pin-carrying portion while the slot 7 is 65 made in the longer fold or flap. Fig. 5 shows the appearance of the ticket after the longer fold has been turned up and the tongue thrust through the slot.

In Figs. 6 and 7, the slot 7 is made in the 70 short fold at the top of the pin-carrying portion of the ticket 1, while the tongue 8 is formed on a preferred long fold or flap so that when the parts are turned together, as shown in Fig. 7, the tongue 8 passes from the outside into the slot 7, leaving a joint between the upper and lower folds.

75

Fig. 8 is a cross-sectional view through the goods and the pin ticket shown in Figs. 6 and 7, the dotted lines in Fig. 8 illustrating the 80 position of the pin 3 after it is first passed through the goods. The figure explains itself.

In Figs. 9 and 10 the tongue and slot shown in the earlier figures of the drawing 85 are replaced by a pasted surface at one end of the flap of the pin ticket, as shown at 10. When the ticket has been attached to the fabric or other material, the flap, that is one half the ticket provided with the glued surface 10 is turned over and when this surface has been wetted and applied to the corresponding surface at the other end of the pin-carrying portion of the ticket, the two ends 90 may be made to stick together, thereby protecting the pin and presenting an absolutely smooth external surface on the ticket.

Figs. 11 and 12 show the glued portion 10 attached to the end of a somewhat longer fold or flap than appears in Fig. 9, so that 100 the glued end after being wetted may be turned over and attached to the under part of the upper fold or pin-carrying portion whereby still another smooth external surface is presented by the ticket after the attachment has been made in the manner described.

The manner in which the pin head is fastened to the pin ticket so as to form a permanent attachment thereto is comparatively 110

a matter of indifference. The mode illustrated is only one of a number which might be employed.

I claim as my invention:

- 5 1. The combination with a material to be marked, of a pin-ticket attached to one side only thereof, the said pin-ticket comprising a portion having a flexible pin permanently attached thereto and having an opening for 10 receiving the said pin after passing through the said material, a portion adapted to be folded directly upon the pin-carrying portion, so as to cover the said pin, and means for fastening the said folded portion to the 15 portion to which the pin is attached.
2. A pin-ticket attachable to one side only of a material to be marked, said pin-ticket comprising a portion lying in a single plane and a pin permanently attached thereto, a 20 flap adjoining and adapted to cover the said portion and its attached pin, and means for fastening the flap to the portion to which the pin is attached, said means comprising two elements between which the pin is attached 25 to the ticket.

3. A pin-ticket comprising a portion having a pin permanently attached thereto, and provided with a slot, a flap adapted to fold over directly upon the pin-carrying portion to cover the pin carried thereby, and a 30 tongue on the flap to extend into the slot and maintain the flap folded upon the pin-carrying portion, the pin being attached to the ticket between the slot and the tongue.

4. A pin-ticket comprising a portion having a pin permanently attached thereto, a flap adapted to fold over directly upon the pin-carrying portion to cover the free end of the pin, and means to fasten the flap folded upon the pin-carrying portion independently 40 of the pin, said means comprising two elements located at opposite ends of the ticket.

Signed at New York, in the county of New York, and State of New York, this 23 day of April, A. D. 1906.

G. ALBIN WALLIN.
